DESIGN.

C. E. HAVILAND.

ORNAMENTATION OF DISHES.

No. 17,069.

Patented Jan. 18, 1887.

UNITED STATES PATENT OFFICE.

CHARLES EDWARD HAVILAND, OF LIMOGES, FRANCE.

DESIGN FOR THE ORNAMENTATION OF DISHES.

SPECIFICATION forming part of Design No. 17,069, dated January 18, 1887.

Application filed November 20, 1886. Serial No. 219,529. Term of patent 14 years.

To all whom it may concern:

Be it known that I, CHARLES EDWARD HAVILAND, a citizen of the United States, residing at the city of Limoges, in the Republic of France, 5 have invented and produced a new and original Design for the Ornamentation of Dishes, which is described and fully represented in the following specification and accompanying facsimiles, forming part of the same.

10 The accompanying facsimile illustrates, as one of the many dishes to which this design is applicable, a perspective view of a plate embodying the design.

The design comprises an outer and an inner 15 border, each composed of sections forming multifarious repetitions of an ornamental figure, hereinafter described. The characteristic feature of each of the multifarious sections of these borders is a curved body-line, from 20 the opposite sides of which curved lobe-like projections extend in opposite directions, which projections are arranged in groups. In the outer border the curved body-line has a scroll-like form. Each section of the outer and inner border has a leaved tendril starting from 25 near one end and crossing it about centrally, while the inner border has one lobe near one end of its sections crowned with dots. These leaved tendrils and crowned lobe, while forming modifying elements, are not essential to 30 the design.

What is claimed is—

1. The design for the ornamentation of dishes, the same consisting of multifarious sections, each composed of a curved body-line having 35 curved lobe-like projections arranged in groups on its opposite sides, substantially as shown and described.

2. The design for the ornamentation of dishes, the same consisting of multifarious sections, 40 each composed of a curved body-line having curved lobe-like projections arranged in groups on its opposite sides and provided with a leaved tendril, substantially as shown and described.

45 3. The design for the ornamentation of dishes, the same consisting of multifarious sections, each composed of a curved body-line having curved lobe-like projections arranged in groups on its opposite sides and provided with 50 a leaved tendril and a lobe crowned with dots, substantially as shown and described.

In testimony whereof I have hereunto set my hand in the presence of two subscribing witnesses.

CH. ED. HAVILAND.
